(57) **CLAIM**

The ornamental design for a reindeer keychain, as shown and described.

DESCRIPTION

FIG. 1 is a front perspective view of a reindeer keychain showing our design;

FIG. 2 is a front elevational view thereof;

FIG. 3 is a right-side elevational view thereof;

FIG. 4 is a left-side elevational view thereof;

FIG. 5 is a top plan elevational view thereof; and,

FIG. 6 is a bottom plan view thereof.

The broken lines in the Figures are for illustrative purposes only and form no part of the claimed design.
